(21) Appl. No.: **29/259,491**

(57) **CLAIM**

(22) Filed: **May 9, 2006**

The ornamental design for a clamping sleeve for telescopic shaft, as shown and described.

(51) **LOC (9) Cl. 08-08**

DESCRIPTION

(52) **U.S. Cl. D8/396**

FIG. 1 is a side view of the clamping sleeve of the present invention, an environment in which the clamping sleeve may be used being shown in broken lines;

(58) **Field of Classification Search D8/356, D8/394-396, 371; 24/570, 67.9; 403/102, 403/109.8; 248/74.2, 215, 227.1, 49, 300, 248/301, 316.7, 51, 489**

FIG. 2 is a perspective view of the clamping sleeve;

See application file for complete search history.

FIG. 3 is a view of one side of the clamping sleeve;

(56) **References Cited**

FIG. 4 is a view of the clamping sleeve from right when the clamping sleeve is oriented as shown in FIG. 3;

U.S. PATENT DOCUMENTS

FIG. 5 is a view of the side of the clamping sleeve opposite to that shown in FIG. 3;
